UNITED STATES PATENT OFFICE.

ALBERT RANDOLPH CHEESEMAN, OF TORONTO, ONTARIO, CANADA.

ELECTRIC IRON.

Application filed January 5, 1924. Serial No. 684,565.

To all whom it may concern:

Be it known that I, ALBERT RANDOLPH CHEESEMAN, a subject of the King of Great Britain, and a resident of the city of Toronto, in the county of York, in the Province of Ontario, Canada, have invented certain new and useful Improvements in Electric Irons, of which the following is the specification.

10 My invention relates to improvements in electric irons, and the object of the invention is to devise simple means for automatically cutting off the current when the heat of the iron rises above a certain pre-
15 determined temperature, thereby eliminating danger of fire, the deterioration of the iron through over heating, and consequent waste of current, and the danger of scorching of the articles being ironed, and it consists essentially of the arrangement and construction of parts hereinafter more particularly explained.

Fig. 1 is a perspective view of an iron body showing the casing broken away to exhibit my device applied to the iron.

Fig. 2 is a plan view of the iron body with the casing removed.

Fig. 3 is a cross sectional view through the iron at the heel end.

30 Fig. 4 is a longitudinal section through the circuit opening and closing lever.

Fig. 5 is a modified construction of finger contact and its support.

In the drawings like characters of reference indicate corresponding parts in each figure.

1 indicates the bottom of the iron, consisting of an ironing plate and the body 2 secured to the ironing plate and within 40 which is located a heating element of any usual construction, the terminals of which I have illustrated at 3 and 4.

5 is a plate of insulating material such as mica, the plate 5 being secured to the body 2 by screws 6.

7 is a slot formed in the plate 5 through which the terminal end 4 of the heating element extends.

8 is a plate of insulating material secured to the heel end of the iron at one side thereof against which is secured a metal piece 9 of conducting material, such piece being preferably right angular in form and secured in position by a correspondingly grooved block of insulating material 10 se-

cured to the heel end of the iron as illustrated at 11.

A vertical portion of the piece 9 extends upward and is provided with an orifice 12. The opposite end of the piece 9 projects inward from the block 10, the terminal end 3 of the heating element being secured to such projecting end as illustrated at 13.

A circuit breaking and making lever is 65 provided, divided into two portions 14 and 15, the portion 15 being in the form of a sleeve provided with a lining of insulating material 16, into which extends the lever member 14, being secured therein by screws 70 16*, as illustrated in Fig. 4.

The outer end of the lever member 15 is connected by a link 17 to the forward end of the iron body 2 by a pin 18. Usually the body 2 is formed of iron and the link 17 75 is formed of brass or other metal having a greater co-efficient of expansion than iron.

The lever formed by the members 14 and 15 is pivoted at 19 to the iron body 2 at a point adjacent to the end of the link 17. 80

It will thus be seen that the link operates upon the short arm of the lever so as to multiply movement in the opposite end which is provided with a projecting finger 20 which extends through the orifice 12 85 so as to fit the same and is of such a form that when the lever is swung it will withdraw from such orifice, remaining in contact with the sides of the orifice until entirely withdrawn therefrom. 90

21 is a strip of ribbon wire which is secured to the member 14 of the circuit making and breaking lever.

22 and 23 are the terminal pins carried by the iron and of the usual construction, the lower end of the pin extending into the interior of the casing and to which the upper ends of the terminal 4 of the heating unit and the upper end of the ribbon wire 21 are respectively connected. 95

It will thus be seen that when a circuit is closed by the finger 20 extending through the perforation 12, that such circuit extends from the terminal pin 23 through the ribbon wire 21, lever member 15, finger 20, piece 9 of conducting material to one terminal end 3 of the heating element, the circuit then passing through the heating element to the other terminal end 4 which is connected to the other terminal pin 22. 105 110

When the iron becomes heated during use, the metal in the iron expands, but the metal of the link 17 being formed of brass or other material having similar qualities, has a greater rate of expansion than the iron and therefore swings the short arm of the lever member 15 outward, such movement being multiplied in the long arm of the lever so that the finger 20, as the link 17 expands, is gradually drawn through the perforation 12.

The length of the finger 20 is so adjusted that when the iron has become heated to a predetermined temperature, such as an ordinary ironing temperature, such finger withdraws from the orifice 12 so as to break contact, thereby breaking the circuit through the heating element of the iron.

As the iron cools, a reverse operation takes place, the link 17 contracting at a greater rate than the contraction of the iron body and therefore swings forward the members 14 and 15 in the opposite direction, carrying the finger 20 again into the orifice 12 so as to again make contact, enabling the temperature of the iron to again rise until the required limit has been reached.

In Fig. 5 I have shown a modified construction of finger in which the outer end of the lever member 15 is provided with an internally threaded orifice 24, (see Fig. 5) in which is screwed a screw pin 25. 26 is a pin formed to fit the orifice 12 and having a flexible connection such as illustrated at 27 to the screw 25 to permit the pin 26 sliding inwardly and outwardly of the orifice 12 when the lever member 14 is swung in one direction or the other.

By the employment of the screw pin 25 the point at which the contact is broken may be varied, in other words, the temperature at which the current is cut out from the heating element may be varied to suit conditions. For instance, the ordinary ironing temperature which is used for domestic ironing is higher than what would be used for the reviving of furs, and by the employ-

ment of my adjustable finger the contact may be adjusted so that the iron may be used for one purpose or the other whenever required.

What I claim as my invention is:

1. In an electric iron, the combination with the body and the element thereof, of a stationary contact carried by the body and connected to one element terminal, a movable contact also carried by the body and connected with the other terminal, a mono-metal rigid bar connected to the iron body at one end and to the movable contact at the opposite end and capable of expansion longitudinally in its own plane when subjected to heat whereby the movable contact brakes contact with the stationary contact during the expansion of the bar and makes contact during the contraction of the bar. 65

2. In an electric iron, the combination with the body thereof and the heating element, of a stationary contact carried by the body connected to one terminal of the element, a swinging lever, a movable contact carried by the lever and insulated therefrom and coacting with the stationary contact, a rigid mono-metal bar connected at one end to the iron body and at the opposite end to the opposite end of the lever and capable of expansion longitudinally in its own plane when subjected to heat. 75

3. In an electric iron, the combination with the body thereof and the heating element, of a stationary contact carried by the body connected to one terminal of the element, a swinging lever, a movable contact carried by the lever and insulated therefrom and coacting with the stationary contact, a rigid mono-metal bar connected at one end to the iron body and at the opposite end to the opposite end of the lever and capable of expansion longitudinally in its own plane when subjected to heat, and means for adjusting the movable contact of the lever to and from the stationary contact. 80 85
ALBERT RANDOLPH CHEESEMAN.
